Primary Examiner—Stella Reid

(57) **CLAIM**

The ornamental design for a vibrator, as shown and described.

DESCRIPTION

FIG. 1 is a side view of a vibrator, showing my new design. FIG. 2 is a side view thereof, rotated 90° from that shown in FIG. 1.

FIG. 3 is a bottom plan view thereof; and, FIG. 4 is a top plan view thereof.

The broken line showing is for illustrative purposes only and forms no part of the claimed design.
